(57) **CLAIM**

The ornamental design for a bag, as shown and described.

DESCRIPTION

A portion of the disclosure of this patent document contains material which is subject to copyright protection. This patent document may show and/or describe matter which is or may become trade dress of Lancel International S.A.. The copyright and trade dress Lancel International S.A. has no objection to the facsimile reproduction by anyone of the patent disclosure as it appears in the Patent and Trademark Office patent files or record, but otherwise reserves all copyright and trade dress rights whatsoever.

FIG. 1 is a front, top view of a bag showing the new design; FIG. 2 is a right side view thereof;

FIG. 3 is a left side view thereof;

FIG. 4 is a top view thereof;

FIG. 5 is a bottom view thereof;

FIG. 6 is a rear, top view thereof;

FIG. 7 is a front, top perspective view thereof;
FIG. 8 is a bottom view thereof in a first alternate configuration;

FIG. 9 is a bottom view thereof in a second alternate configuration; and,

FIG. 10 is a bottom view thereof in a third alternate configuration.

The broken lines shown in the drawings illustrate portions of the bag that form no part of the claimed design.

1 Claim, 10 Drawing Sheets
